UNITED STATES PATENT OFFICE.

ERNEST FRED SCHNEIDT, OF DETROIT, MICHIGAN.

SWIMMING MASK.

Application filed July 1, 1920. Serial No. 393,306.

To all whom it may concern:

Be it known that I, ERNEST F. SCHNEIDT, a citizen of the United States, residing at Detroit, in the county of Wayne and State 5 of Michigan, have invented certain new and useful Improvements in Swimming Masks, of which the following is a specification.

This invention relates to swimming masks and has as its general object to provide a 10 mask which may be readily applied to the head and which will exclude water from the mouth, nostrils, and eyes, and thus remove the cause of intimidation of those learning to swim. Also the mask is designed to render swimming and surf bathing more enjoyable, inasmuch as the head may be submerged without any inconvenience whatsoever.

Another object of the invention is to so 20 construct the mask that when the head is above water the wearer will experience no difficulty whatsoever in breathing in a natural manner.

A further object of the invention is to 25 provide a mask of this type with means whereby the vision of the wearer will not be obstructed so that considerable enjoyment may be had in viewing one's surroundings when entirely submerged.

30 A still further object of the invention is to provide the mask with a breathing tube or a connection for such a tube of such nature that, if desired, a long air tube may be attached thereto so as to permit the wearer 35 of the mask remaining submerged for a considerable period of time, and in fact so long as the intake end of this air tube is maintained above water.

In the accompanying drawings:

40 Figure 1 is a perspective view illustrating one form of the mask embodying the present invention in use;

Fig. 2 is a front elevation illustrating the mask in use;

45 Fig. 3 is a vertical front to rear sectional view through the mask shown in Figs. 1 and 2;

Fig. 4 is a horizontal sectional view taken substantially on the line 4—4 of Fig. 3;

50 Fig. 5 is a side elevation illustrating a slightly modified form of mask;

Fig. 6 is a vertical front to rear sectional view through this form of mask.

55 In all figures of the drawings, the mask is indicated in general by the numeral 1 and the same is preferably formed from compar-

atively thin rubber and will therefore be light in weight and will prove of no discomfort to the wearer. The mask is in the nature of a head covering designed to completely cover the head, and it is provided at its lower side with a neck piece which is indicated in general by the numeral 2 and which is designed to more or less snugly surround or encompass the neck of the wearer and is preferably slightly thicker than the remainder of the mask although not so thick as to preclude stretching to the required extent to permit of it being readily passed over the head. The mask proper is of a shape to generally conform to the general contour of the head and facial features, being molded to provide a nose portion, in that form of the invention shown in Figs. 1 to 4 inclusive, indicated by the numeral 3, and a chin portion indicated by the numeral 4. If desired, however, the mask may be formed with sufficient fullness to render unnecessary the provision of a definite nose portion, as for example as shown in Figs. 5 and 6. In general, however, the mask will as stated conform more or less to the contour of the head and facial features so as to comfortably fit the wearer without producing discomfort or unduly confining the head and face. It will be understood at this point however that the neck portion 2 will be adapted to fit the neck sufficiently snugly to prevent the entrance of water into the mask, but this on the other hand may be accomplished without causing the neck portion to unduly restrict the neck or interfere with breathing.

That portion of the mask which is located immediately in front of the eyes and the bridge of the nose, when the mask is applied, is of slightly greater thickness than the main portion of the mask, as indicated by the numeral 5, and is formed with eye openings indicated by the numeral 6. Into each of these eye openings 6 there is permanently, or, if desired, detachably, fitted a pane 7 of glass, celluloid, isinglass, or in fact any other transparent material suitable for the purpose. In this manner means is provided whereby the wearer of the mask may view his surroundings while completely submerged, and yet no water can enter the mask through the eye openings 6.

That portion of the front of the mask 1 which is in front of the mouth of the wearer when the mask is applied, is also of slightly increased thickness as indicated by the nu-

meral 8, and either fitted through an opening in this portion or molded integral therewith, is a breathing tube 9 which may be of rubber or any other material suitable for 5 the purpose and which includes a portion 10 extending outwardly from the exterior of the mask and a portion 11 which extends into the mask. The latter portion, in the use 10 of the mask, is designed to enter the mouth of the user and when the user is about to submerge, or to dive, this end of the tube may be closed by clinching the same between the teeth so that no water will enter 15 the mask through the tube so long as its inner end is maintained closed in the manner stated. Of course, when the user again brings his head above water, he may relieve 20 the tube of pressure and it will therefore automatically open so that he may breathe without inconvenience.

In that form of the invention shown in Figs. 5 and 6 of the drawings, the portion 10 of the breathing tube 9 may if desired be formed of hard rubber so that there may 25 be attached thereto one end of a breathing tube 12 which may be of any desired length. In order to better support this tube and to prevent the end thereof which is fitted to the portion 10 of the tube 9 being accidentally 30 torn loose, the tube is preferably led upwardly through a sleeve 13 which is preferably molded integral with the thickened portion 5 of the mask substantially at a point opposite the bridge of the nose. The 35 tube 12 may be either frictionally held within this sleeve to prevent slippage or, if found necessary or desirable, it may be

more or less permanently secured in place. The tube may be of approximately the length shown in Figs. 5 and 6 of the drawings or 40 it may be of a length to extend, at its other end, above water so that the wearer of the mask, in this latter instance, may remain submerged for a considerable period 45 of time without any inconvenience. In the former instance, the tube will enable the wearer of the mask to take breath while the nose and mouth are submerged and the top of the head is above water.

Having thus described the invention, what 50 is claimed as new is:

A swimming mask consisting of a head covering of flexible water-proof material constructed to completely envelop the head of the wearer and having a neck portion 55 adapted to encircle the neck of the wearer and be held thereon by its own elasticity, the head covering being provided with a thickened front portion and having glazed sight openings in said portion, an inhaling 60 and exhaling tube forming a mouth piece passing through and being integral with the front portion of the head covering below the sight openings, a sleeve on the exterior of the thickened front portion of the head covering, and a detachable tubular member 65 adapted to form a continuation of the breathing tube and extending upwardly through and retained by said sleeve, terminating substantially level with the top of 70 the forehead portion of the mask.

In testimony whereof I affix my signature.

ERNEST FRED SCHNEIDT. [L. S.]
